UNITED STATES PATENT OFFICE.

WILLIAM B. WAIT, OF NEW YORK, N. Y.

PLATE FOR EMBOSSED PRINTING.

1,136,632.

Specification of Letters Patent. Patented Apr. 20, 1915.

Application filed June 5, 1913. Serial No. 771,911.

To all whom it may concern:

Be it known that I, WILLIAM B. WAIT, a citizen of the United States, residing at New York, in the county of New York and State of New York, have invented new and useful Improvements in Plates for Embossed Printing, of which the following is a specification.

This invention relates to a plate which is designed for embossing characters on a sheet of paper, and essentially adapted for use on an embossing machine of the kind shown in my application Serial No. 732,079 filed November 18th 1912.

15 The plate is formed of thin flexible metal such as aluminum or brass and it has elevations and channels, the elevations having embossed characters, while the channels are provided with elastic strips for protecting 20 the impressions produced by the opposite plate.

The object of the invention is to provide the elastic strips with devices for holding the strips rigidly into the channel. Each elastic strip when fitted into a channel is kept 25 under tension by means of its holding devices, and the strip is thereby held snugly along its entire length into the channel.

30 The novel features of the invention are more fully described in the following specification and claim, and illustrated in the accompanying drawings in which:

Figure 1 represents a vertical section taken along the line $x-x$ Fig. 2, of a plate 35 embodying this invention. Fig. 2 is a plan view of the same. Fig. 3 is a section taken along the line $y-y$ of Fig. 2. Fig. 4 is a similar section showing a curved plate. Fig.

5 is a perspective view of the end portion of a strip. In this drawing is shown a plate 40 having a series of channels a and elevations b with embossed characters stamped on the elevated portions of the plate. In each channel is arranged a rubber strip c provided at each end with a hook member d secured to 45 the strip. The hook member is preferably formed of wire and it is fastened to the rubber by bending one end to firmly clasp the end portion of the rubber. The hook end of the member is adapted to engage the 50 edge portion or an eye formed in the plate. The elastic strip when fitted into a channel is somewhat shorter than the width of the plate and by hooking each end of the strip to the plate it stretches the elastic to embrace 55 the channel and prevent outward movement or displacement of the strip along its entire length.

The plate may be employed for a form or for attachment to a cylinder, and is used 60 in connection with an embossing machine.

I claim:

An embossing plate having elevations and channels, an elastic strip arranged in each of the channels, a hook member secured to 65 each end of the strip adapted to tension the strip thereby holding it firmly in the channel and engage the plate.

In testimony whereof I have hereunto set my hand in the presence of two subscribing 70 witnesses.

WILLIAM B. WAIT.
